* cited by examiner

Primary Examiner — Zenia Bennett(74) Attorney, Agent, or Firm — Knobbe Martens Olson & Bear LLP(57) CLAIM

I claim the ornamental design for a counterweight for jewelry pendant, as shown and described.

DESCRIPTION

FIG. 1 is a perspective view of one embodiment of a new design for a counterweight for jewelry pendant;

FIG. 2 is a front view thereof;

FIG. 3 is a rear view thereof;

FIG. 4 is a right side view, the left side being a mirror image;

FIG. 5 is a top view thereof;

FIG. 6 is a bottom view thereof; and,

FIG. 7 is a front view with an embellishment shown in broken lines.

The broken lines are for illustrative purposes only and form no part of the claimed design.
